(No Model.)

R. CARTWRIGHT.
WELDING ROLL.

No. 400,828.

Patented Apr. 2, 1889.

Witnesses,

Smith & Denison

UNITED STATES PATENT OFFICE.

ROBERT CARTWRIGHT, OF ROCHESTER, ASSIGNOR OF ONE-HALF TO WILLIAM A. SWEET, OF SYRACUSE, NEW YORK.

WELDING-ROLL.

SPECIFICATION forming part of Letters Patent No. 400,828, dated April 2, 1889.

Application filed July 28, 1888. Serial No. 281,318. (No model.)

To all whom it may concern:

Be it known that I, ROBERT CARTWRIGHT, of Rochester, county of Monroe, in the State of New York, a citizen of the United States, have invented certain new and useful Improvements in Welding-Rolls, of which the following is a specification, reference being had to the accompanying drawings, in which—

Figure 1 is a vertical sectional elevation.
10 Fig. 2 is a plan view of one side of the welding-roll removed from the carrying-frame, the frame being shown in dotted lines.

This invention relates to the construction of rolls for use in welding-machines, whether 15 the roll have simply a forward movement or whether it be connected to mechanism adapted to impart to it a reciprocating motion.

The object of my invention is to produce a 20 welding-roll adjustable to different thicknesses of metal and having only the minimum of friction.

My invention consists in the several novel 25 features of construction and operation hereinafter described, and which are specifically set forth in the clauses of the claims hereunto annexed. It is constructed as follows:

A represents the part of the frame of the machine, and where a reciprocatory motion is imparted to the welding-roll this frame is 30 stationary, or it may be stationary also when the work is fed through under the roll without any reciprocation of either the work or the roll.

B B are the side arms of the frame in which 35 the welding-roll is journaled, and when desired a reciprocatory motion may be imparted to this frame in any ordinary manner.

C is the main arbor, which is loose in its 40 bearings in the frame B. Upon this arbor, and upon either side of the main arbor C, I mount the supporting-rollers D upon friction- 45 bearings, each upon its own independent rollers, and the welding-roll E is in like manner mounted upon friction-rollers 2 independent of the friction-rollers 1 1, so that the supporting-rollers and the welding-roll are all mounted upon independent friction-roller bearings, and all of these friction-bearings are mounted upon and inclose the main arbor C, and all operate upon the periphery 50 of the main arbor entirely independent of each other, and also by their friction upon the main arbor they cause that to rotate more or less, the result being that when in opera-

tion each and every friction-roll is constantly 55 wearing against a different part of the main arbor, so that the main arbor is never worn out of true.

At 3 3 I show a trackway upon which the supporting-rollers D travel. This trackway 60 is adjustable by means of the slotway 4, (shown in dotted lines,) and through which the bolts 5 are inserted into the frame A, and by adjusting this slightly vertically I adapt the rolls to be used upon thick or thin work, 65 especially when welding the joint of a pipe, where I use one welding-roll inside and one outside of the pipe, one being vertically above the other.

To prevent the track from slipping back, I 70 insert thick or thinner shims into the space 6 between the track and frame A. This trackway may be of any length desired, or sufficient to permit the proper reciprocation of the roll.

It will be observed that all of the strain of 75 the welding-pressure on the roll E is transmitted to the arbor C, and thence to the supporting-rolls D and trackway 3, and that the reciprocatory movement of the welding-roll 80 does not abrade the metal at the weld, but that, on the other hand, the operation of the rolls is to knead the heated metal at the weld, thereby preserving the fiber intact and kneading it together, and consequently making 85 the iron at the weld substantially homogeneous.

What I claim as my invention, and desire to secure by Letters Patent, is—

1. The welding-roll consisting of a welding-roller and independent supporting-rolls, 90 all mounted upon independent friction-roll bearings, which are themselves mounted upon one arbor, in combination with a trackway for the supporting-rolls.

2. A welding-roll consisting of a welding-roller, independent supporting-rollers, all mounted upon friction-bearings bearing upon an arbor loose in its bearings, and a trackway mounted adjustably upon the main frame 100 of the machine and carrying the supporting-rollers.

In witness whereof I have hereunto set my hand this 1st day of May, 1888.

ROBT. CARTWRIGHT.

In presence of—

H. P. DENISON,
C. W. SMITH.
